[57] CLAIM

The ornamental design for a combination car seat and stroller, as shown and described.

DESCRIPTION

FIG. 1 is a rear elevational view of a combination car seat and stroller showing my new design;

FIG. 2 is a front elevational view thereof;

FIG. 3 is a left side elevational view thereof, with the handle in lowered condition;

FIG. 4 is an enlarged perspective view of a detached

seat member of the combination car seat and stroller;
FIG. 5 is an enlarged perspective view of a detached carriage member of the combination car seat and stroller.
